MULTI-STAGE VACUUM DEGASIFIER

Joseph F. Sebald, Bloomfield, N. J., assignor to Worthington Corporation, Harrison, N. J., a corporation of Delaware

Application April 16, 1954, Serial No. 423,560

13 Claims. (Cl. 183—2.5)

This invention relates generally to water treating apparatus and more particularly to an improved multi-stage vacuum degasifier that requires relatively lighter, and smaller, hence less costly, vacuum equipment, and at the same time is designed to meet the limited height and space problems of many installations.

It is well known that raw water contains entrapped and dissolved non-condensable gases such as oxygen, CO₂, NH₃, which it is advantageous to remove before the water is put to use in connection with a process or installation. The removal or release of these entrapped and dissolved gases being a function of the pressure in the equipment which is utilized for degasification.

One vacuum degasifier for this purpose is illustrated in my copending application Serial No. 323,625, which includes means for increasing the efficiency of gas removal by providing vapor flow lanes for equalizing the pressure throughout the degasifying tower, allowing the use of lighter, smaller and less costly vacuum equipment to obtain the equivalent or greater reduction in pressure than previously obtained in similar equipment.

In U. S. Patent No. 2,080,151 to Powell et al., it was shown that increased degasification can be obtained through a two chamber arrangement, operating in series with the vacuum in the second compartment greater than the first.

The present invention covers an improved multi-stage degasifier utilizing two or more compartments having means therebetween acting both to deliver fluid from one compartment to its adjacent compartment and as a seal between these compartments, and which further utilizes in each compartment the vapor flow lane principles of my above mentioned copending application, whereby lighter, smaller and less costly vacuum equipment than has heretofore been utilized by vacuum degasifiers of the same capacity, may be used thereon to produce the same or a greater reduction in pressure in the present apparatus.

Accordingly, it is an object of the present invention to provide a vacuum degasifier designed and adapted to meet limited height or space requirements which will supply the required volume of fluid.

It is another object of the present invention to provide a vacuum degasifier which will provide an equal or increased amount of degasification of the fluid passing therethrough with vacuum equipment which is lighter, smaller and less costly.

With these and other objects in view, as may appear from the accompanying specification, the invention consists of various features of construction which will be first described in connection with the accompanying drawings, showing a multi-stage vacuum degasifier of a preferred form embodying the invention, and the features forming the invention will be specifically pointed out in the claims.

In the drawings:

Figure 1 is a side elevation partly in section showing the invention.

2

Figure 2 is a cross section taken on the line 2—2 of Fig. 1.

Figure 3 is a cross section taken on the line 3—3 of Fig. 1 of the interior of the second stage compartment.

5 Figure 4 is a cross section taken thru line 4—4 of Fig. 3.

Figure 5 is a cross section taken thru line 5—5 of Fig. 4.

Figure 6 is a side elevation partly in section showing 10 another form of the invention.

Figure 7 is a cross section taken on the line 7—7 of Fig. 6.

Figure 8 is a cross section taken on the line 8—8 of Fig. 6.

15 Figure 9 is a cross section taken thru line 9—9 of Fig. 8.

Figure 10 is a cross section taken thru line 10—10 of Fig. 9.

Referring more particularly to the drawings, the improved degasifier 1 as shown in Fig. 1 includes an elongated tower 2 having a partition 3 extending across the approximate horizontal mid-section of the tower and inclined downwardly forming an inlet degasifying chamber 4 in the upper section and an outlet degasifying chamber 5 in the lower section. The partition is provided with an opening 6 at its lowest point and from this opening a vertical channel-shaped partition or leg 7, connected at its upper most end to the opening and at its open sides to the inner wall of the tower, forms a 20 downflow passage 8 substantially rectangular in cross section and extending downwardly to a point adjacent the bottom of the tower.

A second channel shaped leg 9 in spaced relation and parallel to the first leg has its lower end and side 35 attached at the lower end of the outlet degasifying chamber 5 and its open side connected to the leg 7 so as to form an upflow passage 10 and a fluid chamber 11 to connect the respective flow passages 8 and 10 to each other whereby a U tube seal generally designated 12 is formed, which acts when filled with fluid during the 40 operation of the degasifier, as a fluid seal between the inlet and the outlet chamber.

The raw water enters the degasifier thru the inlet manifold 13 which extends diametrically across the upper 45 section of the inlet chamber 4 and passes thru a plurality of pipes or conduits 14 extending outwardly from the manifold. A plurality of spray valves 15 mounted in spaced relation on the underside of the pipes 14 distribute the water in thin streams over the top of the packing assembly 16, more fully shown and described in my copending application Serial No. 323,625, filed Dec. 2, 1952. The packing assembly is mounted in suitable 50 manner to the walls of the tower. A baffle 17, also supported by the walls of the tower, encloses the spray area 55 confining the peripheral annular liquid spray to the top of the packing assembly. The fluid passes by gravity flow downwardly over the packing arrangement shown in Figs. 2 and 3, in the degasifying space. In cascading over the many tiers of horizontal slats, the flow is 60 repeatedly broken into fine particles increasing the surface area and thereby facilitating the release of the non-condensable gases from the liquid during this downward pass.

To further induce the release of the non-condensable 65 gases a partial vacuum is maintained in the chamber by a small steam jet ejector 18 located at the crown of the tower which is well known in the art and hence not more fully described herein. The ejector is also used to remove the gases as they are separated from the water by sweeping them off through the suction caused by the 70 current of steam passing thru the ejector. This prevents any partial air pressure from building up in the chamber or the unit would become air-bound.

The water passes thru the packing assembly 16 and falls to the inclined partition 3 from there flowing down thru the opening 6 and entering the downflow passage 8 of the fluid seal 12. As the level of the water in the U-tube rises above the chamber 11 the inlet degasifying chamber is sealed from the outlet degasifying chamber.

The second steam jet ejector 19 maintains a vacuum in the outlet chamber which, because of the fluid seal is able to beat a greater negative pressure than the inlet chamber. It is this same difference of pressure that forces the fluid to pass from one chamber to another thru the U-tube seal. The greater pressure in the inlet chamber forces the level of the fluid down in the downflow passage 8 causing the level to rise in the upflow passage 10. The top of the leg 9 forms a weir 20 over which the water flows into the distributing trays 21.

The distributing trays 21 are supported by the side walls and serve to uniformly distribute the water over the packing assembly. As the fluid fills the tray it spills over the edges which are provided with serrated rims. Each notch on the rim is located in such a manner that the water will fall to one of the slats of the packing assembly. The fluid is thus again dispersed into small droplets to allow further escape of the non-condensable gases. The fluid passes downward by gravity flow thru the packing and collects in the storage or collection space 23 in the lower portion of the shell where it is drawn off thru a suitable outlet 24 by means of a pump 25.

The ejector 19, maintaining the vacuum in the outlet chamber, draws off the gases released in the outlet chamber in the same manner as previously stated, receiving its motivating steam through conduit 26 from a suitable source not shown. The ejector is mounted in conduit 27 having its inlet 28 in the upper section of the outlet chamber and its discharge end directed into the spray region of the inlet chamber. The released gases are carried by the conduit 27 upward to the spray region of the inlet chamber and released therein, the non-condensable gases rising thru the spray are vented off with those gases being released from the inlet chamber. The steam, when introduced into the cold spray, is condensed and enters the process with the new raw water.

Figure 6 of the drawings shows another form of the invention which differs from the form shown in Figures 1 to 5 of the drawings primarily in the fact that the modified form of the invention has the inlet and outlet chambers adjacent to each other rather than one above the other. The modified form is obviously more suitable to installations where height limitations are concerned.

The modified form of the invention, includes a shell 29, that is larger in diameter but shorter in height than the form shown in Fig. 1, with two adjacent degasifying chambers 30 and 31. The inlet chamber 30 is separated from the outlet chamber 31 by a first partition 32 extending downward from the top of the shell to a point adjacent the bottom of the shell and a second partition 33 connected to the bottom of the shell extending upward in spaced relation and parallel to the first partition forming a fluid passage 34 across the diameter of the shell between the partitions.

It will be understood that while the fluid passage 34 is indicated as equal to the width of the shell that it may be varied as will be understood by those skilled in the art as by extending the member 32 to the bottom of the shell 29 and providing an opening therethrough adjacent the bottom to coat with a channel member attached as indicated for the member 9 in the form of the invention illustrated in Figures 1 and 3 of the drawings.

A water inlet manifold 35 extends across the inlet chamber with pipes 36 extending transversely from the manifold. The raw water enters thru the manifold, passes thru the pipes and is sprayed through a plurality of spray valves 37 over the top of the packing assembly 38. The baffle 39 confines the spray to the top area of the packing assembly. The fluid passes by gravity flow downward

over the packing assembly breaking into small droplets to release the non-condensable gases and collects at the bottom 40 of the chamber.

The opening 41 provided at the bottom of the first partition permits the water to pass from the inlet chamber into the upflow passage 34 thus forming a fluid seal generally designated 42 between the chambers. The greater pressure in the inlet chamber forces the level of the fluid to rise in the passage and flow over the weir 43 into distributing trays 44, similar to those previously mentioned, and passes downward thru the packing assembly 45. The deaerated fluid is stored at the bottom 46 of the chamber and is removed by pump 47 as needed thru the outlet 48.

A steam jet ejector 49 is used in the outlet chamber to remove the released non-condensable gases and is exhausted into the spray region 50 of the inlet chamber where the steam is condensed and the gases are vented off with those released in the inlet chamber thru a second ejector 51.

For particular installations where a greater degree of purity of the fluid is required, the present invention is modified by increasing the number of stages. One or more chambers are added between the inlet and outlet chambers, altering the size of the shell accordingly in height or width, depending on space conditions. Each chamber is maintained at a lower pressure than the one preceding it by its own ejector, each ejector discharging through conduits into the upper section of the packing assembly in the preceding chamber where condensation can take place. The chambers are separated one from the other by the fluid seal in the same manner as described for the other forms of the invention. The dimensions of the fluid seals being a function of the difference in pressure of adjacent chambers. Thus the partial pressure of the gas in the outlet chamber will approach zero, necessary to produce maximum degasification.

It will be understood that the invention is not to be limited to the specific construction or arrangement of parts shown, but that they may be widely modified within the invention defined by the claims.

What is claimed is:

1. In a multi-stage vacuum degasifier, a plurality of degasifying chambers including an inlet chamber to receive fluid to be degasified and an outlet chamber having an outlet for removing degasified fluid, packing assemblies in each of said chambers forming vapor flow lanes therein, fluid passage means between each of said degasifying chambers including, an upflow leg of predetermined height to form a fluid seal between each of said chambers whereby chambers on opposite sides of said seal may be maintained at different sub-atmospheric pressures and at respectively lower pressures from said inlet stage degasifying chamber to said outlet stage degasifying chamber, means for maintaining each of said chambers at their respective predetermined sub-atmospheric pressures, said means for maintaining the sub-atmospheric pressures for each of said chambers other than the inlet chamber having their outlets communicating with a chamber at higher pressure to deliver freed gases from chamber to chamber and to said inlet chamber, and means on said inlet chamber for passing said freed gases to atmosphere.

2. In a multi-stage vacuum degasifier as claimed in claim 1 wherein said means for maintaining said chambers at sub-atmospheric pressures and to remove freed gases therefrom includes vacuum producing means connected to each of said chambers, said vacuum producing means having its inlet connected to said inlet degasifying chamber exhausting to atmosphere, and said other vacuum producing means having their outlets connected to a chamber at higher pressure.

3. In a multi-stage vacuum degasifier as claimed in claim 1 wherein said means for maintaining said chambers at sub-atmospheric pressures and to remove freed gases includes ejectors connected to each of said cham-

bers, said ejectors for said inlet degasifying chamber exhausting to atmosphere, and each of said other ejectors exhausting into another of said chambers at a higher sub-atmospheric pressure than the chamber to which they are connected.

4. In a multi-stage vacuum degasifier, an inlet degasifying chamber and an outlet degasifying chamber, packing assemblies in each of said chambers forming vapor flow lanes therein, means for delivering raw water to said inlet degasifying chamber, and said outlet degasifying chamber having an outlet for removing degasified fluid therefrom, fluid passage means having a predetermined height communicating at one end with said inlet degasifying chamber and at the other end to said outlet degasifying chamber to form a fluid seal therebetween and to allow said outlet degasifying chamber to be maintained at a lower sub-atmospheric pressure than said inlet degasifying chamber, means connected to each of said degasifying chambers for maintaining said chambers at the desired sub-atmospheric pressure and to remove freed gases from said vacuum degasifier, said means for maintaining the outlet chamber at the desired sub-atmospheric pressure having its outlet communicating with said inlet chamber.

5. In a multi-stage vacuum degasifier, partition means transversely disposed therein to form a first stage degasifying chamber and a second stage degasifying chamber, means for delivering fluid to be degasified to said first stage degasifying chamber, said second stage degasifying chamber having an outlet for removal of degasified fluid, packing assemblies in each of said chambers forming vapor flow lanes therein, fluid passage means having a predetermined height operatively associated with said partition means and forming a fluid seal between said chambers to allow said second stage degasifying chamber to be maintained at a lower sub-atmospheric pressure than said first stage degasifying chamber, and means connected to the upper end of each of said chambers to maintain the desired sub-atmospheric pressure in its respective chamber, said means for maintaining the second stage degasifying chamber at its desired sub-atmospheric pressure having its outlet operatively connected to said first stage degasifying chamber, and said fluid passage means to pass fluid from said first stage degasifying chamber to said second stage degasifying chamber by gravity and differential pressure between said chambers.

6. In a multi-stage vacuum degasifier as claimed in claim 5 wherein said means for maintaining each of said chambers at the desired sub-atmospheric pressure includes vacuum producing means connected to the upper end of each of said chambers, said vacuum producing means connected to the upper end of said first stage degasifying chamber exhausting to atmosphere, and said vacuum producing means connected to said second stage degasifying chamber having an outlet communicating with said first stage degasifying chamber.

7. In a multi-stage vacuum degasifier as claimed in claim 5 wherein said partition means is mounted transversely of the longitudinal plane of said vacuum degasifier and at an angle thereto to form a sloping lower wall for said first stage degasifying chamber, said partition having its lower end in communication with the upper end of said fluid passage means and to pass fluid thereto from said first stage degasifying chamber by gravity flow.

8. In a multi-stage vacuum degasifying chamber as claimed in claim 5 wherein said partition means is mounted substantially parallel to the longitudinal plane of said degasifier and forms a sidewall of said first stage degasifying chamber, and said partition means having an outlet at its lower end to provide continuous communication between said inlet degasifying chamber and said fluid passage means.

9. In a multi-stage vacuum degasifier, a tank, a partition medially disposed in said tank transversely of the vertical plane forming a common wall for a first stage

degasifying chamber and a second stage degasifying chamber, packing means in each of said chambers forming vapor lanes therein, means in the upper end of said first stage degasifying chamber connected to a source of raw water for delivering said water to the packing means in said first stage degasifying chamber, said second stage degasifying chamber having an outlet for degasified water, a U-shaped fluid passage means of a predetermined height connected between said first stage degasifying chamber and said second stage degasifying chamber and forming a fluid seal therebetween to allow said second stage degasifying chamber to be maintained at a lower sub-atmospheric pressure than said first stage degasifying chamber, a first vacuum producing means having its inlet end connected to said second stage degasifying chamber and exhausting into said first stage degasifying chamber to maintain said second stage degasifying chamber at the desired sub-atmospheric pressure and to remove freed gases therefrom, a second vacuum producing means connected to said first stage degasifying chamber and exhausting to atmosphere to maintain said first stage degasifying chamber at sub-atmospheric pressure and to remove freed gases from said vacuum degasifier, said passage means to pass fluid therethrough by gravity and under action of the differential pressure between said chambers.

10. In a vacuum degasifier as claimed in claim 9 wherein said U-shaped passage means forming a fluid seal includes a downflow channel and an upflow channel in continuous communication at their lower ends, said downflow channel having its upper end connected to said partition and in communication with said first stage degasifying chamber to receive fluid therefrom by gravity, and said upflow channel having its upper end in communication with said second stage degasifying chamber to deliver fluid thereto under action of the differential pressure between said chambers.

11. In a multi-stage vacuum degasifier, a tank, a pair of spaced partitions medially disposed in said tank substantially to the vertical plane thereof and forming an upflow passage therebetween, said partitions forming a first stage degasifying chamber and a second stage degasifying chamber in said tower on opposite sides of said upflow passage, packing means in each of said chambers forming vapor flow lanes therein, means for supplying water to be degasified to said first stage degasifying chamber, said second stage degasifying chamber having an outlet for degasified water, said upflow passage in continuous communication at its lower end with said first stage degasifying chamber and to receive fluid therefrom, said upflow chamber having an outlet a space height from said lower end communicating with said second stage degasifying chamber to form a fluid seal between said chambers and to allow said second chamber to be maintained at a lower pressure than said first stage degasifying chamber, means for maintaining each of said chambers at the desired sub-atmospheric pressures, said means for maintaining the second stage degasifying chamber at its desired sub-atmospheric pressure having its outlet operatively connected to the first stage degasifying chamber, and said upflow passage to pass water from said first stage degasifying chamber to said second stage degasifying chamber by gravity flow and under action of differential pressure between said chambers.

12. In a multi-stage vacuum degasifier, a tower, a first partition medially disposed in said tower substantially parallel to the vertical plane thereof and forming a common wall for a first stage degasifying chamber and a second stage degasifying chamber, a second partition in said second stage degasifying chamber spaced from said first partition to form an upflow passage therebetween, packing means in each of said chambers forming vapor flow lanes, means for supplying fluid to be degasified to said first stage degasifying chamber, said second stage degasifying chamber having an outlet for degasified fluid, said upflow passage having a predetermined height and

having the lower end thereof in continuous communication with said first stage degasifying chamber to receive fluid therefrom and its upper end communicating with the upper end of said second stage degasifying chamber to form a fluid seal between said chambers, vacuum producing means connected to each of said chambers to maintain said second stage degasifying chamber at a lower sub-atmospheric pressure than said first stage degasifying chamber, said vacuum means for maintaining the second stage degasifying chamber at the desired sub-atmospheric pressure having its outlet operatively connected to said first stage degasifying chamber and said upflow passage to pass fluid from said inlet degasifying chamber to said outlet degasifying chamber by gravity and under action of differential pressure between said chambers.

13. In a multi-stage vacuum degasifier as claimed in claim 12 wherein said vacuum producing means for maintaining each of said chambers at the desired sub-atmos-

5
